UNITED STATES PATENT OFFICE

ROSWELL C. VAN SICKLE, OF WILKINSBURG, PENNSYLVANIA, ASSIGNOR TO WESTINGHOUSE ELECTRIC & MANUFACTURING COMPANY, A CORPORATION OF PENNSYLVANIA

CIRCUIT BREAKER

Application filed December 9, 1927. Serial No. 238,801.

My invention relates to circuit interrupters and more particularly to the closing mechanisms therefor.

One object of my invention is to provide an actuating mechanism for a circuit interrupter wherein the maximum force shall be exerted at the time when the resistance to closing is greatest.

Another object of my invention is to provide a main actuating mechanism for a circuit interrupter that shall be assisted by an auxiliary actuating mechanism at the point of maximum load in the operation of a circuit interrupter.

15 A further object of my invention is to provide an auxiliary actuating mechanism to be connected to the main actuating mechanism by a lever system that shall control the amount of force exerted by the said auxiliary mechanism.

20 A still further object of my invention is to provide a plurality of actuating mechanisms for a circuit interrupter that shall be energized simultaneously, but that shall be connected in such manner that the auxiliary mechanism becomes increasingly effective during the closing operation.

In circuit-breaker-closing mechanisms of the ordinary types, resistance to closing is at 25 a maximum when the contact members first come into engagement. This is especially true when the circuit interrupter is designed for carrying large currents, since, in such cases, a magnetic repulsion will act on the 30 moving member when the contact members are in engagement. In designing actuating mechanisms it has been the practice in the art to design a closing mechanism adapted to exert sufficient force to overcome this maximum closing resistance with the result that the decrease in load thereafter causes the moving members to slam at the end of the 35 operation. This causes severe strain on all the moving parts that will eventually cause 40 distortion or the final breaking of the members.

In practicing my invention, I have designed an auxiliary closing mechanism that is linked to the main mechanism in such manner that an increasing force is exerted there-

by to assist the said main mechanism during its operation with a force that rises to a maximum at the time of initial engagement of the contact members.

According to the drawings:

Figure 1 is a side view, in elevation, of a particular embodiment of my invention in closed position; and

Fig. 2 is a view similar to that of Fig. 1 but showing the breaker in open position.

My invention comprises, in general, an auxiliary actuating mechanism 1, which will herein also be known as a booster mechanism and which is connected, by the lever system 2, to the main actuating mechanism 3 which may be of any design. The one herein shown is a preferred form described in Patent No. 1,807,020 issued May 25, 1931, to R. C. Van Sickle and S. T. Schofield, and assigned to the Westinghouse Electric & Manufacturing Company, and will not be herein described in detail. The main actuating mechanism 3 includes an actuating arm 4, which is connected to the movable contact member 41 of a circuit breaker 42 having stationary contacts 43.

The main closing mechanism described in the copending application aforesaid was designed to produce a maximum pull at the time the contact members first come into engagement. When employed to operate circuit interrupters carrying very high current, it was found that an additional resistance to closing was present. My auxiliary mechanism was invented to supply the desired correction, under the conditions first mentioned, which will now be described in detail.

The actuating arm 4 of the main operating mechanism 3 contains an extension 5 and pin 6 that constitute the means by which the booster mechanism 1 is connected to the main actuating device 3. The pin 6 pivotally supports an eye bolt 7 that has an elongated slot 8 therein to form a slidable connection on the pin 6. The eye bolt 7 is adjustably connected, by a threaded section 9, to a link 11. The other end of the link 11 is connected, by a pin 12, to a bell crank 13 that is pivotally connected, at its center, to a frame 15 of the booster mechanism 1, by a pin 14. The other

end of the bell crank 13 is connected, by pin 16, to a link 17, the other end of which is connected, by pin 18, to a bell crank 19 of the booster mechanism 1.

5 The bell crank 13 is provided with a stop member 21 that is designed to engage an extension 22 of the link 17 to prevent the toggle formed thereby from going over-center, as shown in Fig. 2.

10 The bell crank 19 is pivotally connected, by a pin 23, to the frame 15 and its other end is connected by a pin 24, to a link 25 that is pivotally attached, by a pin 26, to a movable core 27 of the booster mechanism 1. The movable core 27 is slidably contained within a coil 28 and engages a stationary core member 29 when in closed position. An adjustable stop member 32 on the bell crank 19 cooperates with a projection 33, when in open position, 15 as shown in Fig. 2 and is employed to regulate the amount of travel of the movable core 27. Any suitable control circuit may be provided for the actuating coils or solenoids of the main and auxiliary actuating mechanisms, such as that shown in Fig. 1, in which 20 the two coils are placed in series with a battery 35 and a control switch 36 by means of conductors 34.

25 Assuming the circuit interrupter to be in 30 open position, as shown in Fig. 2, when the control switch 36 is closed, the main actuating mechanism 3 and the booster mechanism 1 are simultaneously energized. The force caused by such energization of the coil 28 moves the 35 core 27 upward, at which time, the force exerted through the bell crank 19, the link 17 and the bell crank 13 is at a minimum because the members of the toggle thus formed are in substantial alinement.

40 As the actuating lever 4 of the main actuating mechanism 3 is rotated in a counter clockwise direction, the link 11 moves upwardly to turn the bell crank 13 in a clockwise direction, thereby opening the toggle 45 formed between the bell crank 13 and the link 17 and permitting the booster mechanism 1 to exert an increasing force upon the actuating lever 4 until such position in the circuit-interrupter operation is reached that the 50 contact members 41 and 43 become engaged, at which time, a maximum force is exerted by the booster mechanism 1. The increase in effective force is due to the fact that the 55 opening movement of the toggle referred to increases the ratio of movement of the core 27 to movement of the arm 4 and the circuit breaker 42. Thereafter, the movable core member 27 becomes seated on the stationary 60 core member 29, as shown in Fig. 1, after which the booster mechanism 1 is no longer effective, and the main actuating mechanism 3 completes the operation. The continued movement of the actuating mechanism 3, after 65 the booster mechanism 1 comes to rest, is

made possible by the movement of the pin 6 in the slot 8 of the eye-bolt 7.

Upon the opening movement of the main actuating member 3, the actuating lever 4 moves in a clockwise direction to turn the bell crank 13 in a counter clockwise direction, thereby permitting the moving solenoid member 27 to drop until the stop member 32 comes into engagement with the projection 33, at 70 which time, the stop 22 of the link 17 comes into engagement with the stop member 21 of the bell crank 13 to prevent the pin 16 from travelling over-center. In this position, the booster mechanism 1 is once more in a position 75 to be operated.

It will thus be seen that I have invented a booster mechanism for a main actuating mechanism that is designed to apply an increasing force to the said main actuating mechanism, which force is at a maximum at the time the contact members of the circuit interrupter become engaged. This is the position of maximum closing load and thereafter the booster mechanism ceases to be effective so that the remainder of the closing operation will be accomplished without the slamming that has heretofore been present in similar actuating mechanisms.

It is to be understood that such changes in the form, arrangement and connection of parts of my invention may be made as shall fall within the scope of the appended claims.

I claim as my invention:

1. The combination with an operating mechanism, of a booster mechanism, and a lever system joining the two mechanisms comprising a toggle for controlling the effective force of the said booster mechanism.

2. The combination with a main actuating device and an auxiliary actuating device, of means for uniting the two devices comprising a bell crank and a pair of levers, the one lever and an arm of the bell crank forming a toggle that increases the effective force of the auxiliary device to exert a maximum effect at a predetermined point during the operation of the main device.

3. The combination with a main and an auxiliary actuating device, of means for uniting the two devices comprising a lever system embodying means for increasing the effective force of the auxiliary device from substantially zero at the beginning of, to a maximum at a predetermined point during the operation of the main device.

4. The combination with a main and an auxiliary actuating device, of means for operating the said two devices simultaneously, means for uniting the two devices comprising a lever system embodying means for increasing the effective force of the auxiliary device from substantially zero at the beginning of, to a maximum at a predetermined point during the operation of the main device.

5. The combination with a main and an auxiliary actuating device, of means for uniting the two devices comprising a lever system embodying means for increasing the effective force of the auxiliary device from zero at the beginning of, to a maximum at a predetermined point during, the operation of the main device, after which the auxiliary device ceases to be effective. 70
6. The combination with a main and an auxiliary actuating device, of means for operating the said two devices simultaneously, means for uniting the two devices comprising a lever system embodying means for increasing the effective force of the auxiliary device from substantially zero at the beginning of, to a maximum at a predetermined point during, the operation of the main device, after which the auxiliary device ceases to be effective. 75
7. In a switch mechanism having separable contact members designed to carry heavy currents and in which a blowout effect is produced when the said contact members touch on closing, an actuating mechanism for operating the separable contact members, an auxiliary actuating mechanism, a lever system connecting the two mechanisms which increases the effective force exerted by the auxiliary mechanism to a maximum substantially at the time the said contact members touch. 80
8. A mechanism for actuating an operated device comprising the combination of a main and an auxiliary actuating device, and a lever system for linking said two actuating devices together, said lever system being constructed and arranged to increase the effective force of the auxiliary actuating device to a maximum at the point in the operation of the operated device at which it imposes the greatest load on the actuating mechanism. 85
9. The combination with a circuit breaker having separable contacts, of a closing mechanism therefor comprising a main and an auxiliary actuating device, and a lever system for linking said two actuating devices together, said lever system being constructed and arranged to increase the effective force of the auxiliary actuating device to a maximum at the point in the closing movement of the circuit breaker at which the contacts first engage. 90
10. The combination with a circuit breaker, of a closing mechanism therefor comprising a main and an auxiliary actuating device, and a lever system for linking said two actuating devices together, said lever system increasing the ratio of movement of the auxiliary actuating device to movement of the circuit breaker during the closing movement, to a maximum at the moment the contacts of the circuit breaker first engage. 95
11. The combination with a circuit breaker, of a closing mechanism therefor compris- 100
12. The combination with a circuit breaker, of a closing mechanism therefor comprising a main and an auxiliary actuating device, and a lever system for linking said two actuating devices together, said lever system comprising a toggle arranged to increase the ratio of movement of the auxiliary actuating device to movement of the circuit breaker, during the closing movement, to a maximum at the moment the contacts of the circuit breaker first engage. 105
13. The combination with a circuit breaker, of a closing mechanism therefor comprising a main and an auxiliary actuating device, and a lever system for linking said two actuating devices together, said lever system comprising a toggle arranged to increase the ratio of movement of the auxiliary actuating device to movement of the circuit breaker, during the closing movement, to a maximum at the moment the contacts of the circuit breaker first engage, said lever system thereafter rendering the auxiliary actuating ineffective to apply any force to the circuit breaker. 110
14. The combination with a circuit breaker, of closing mechanism therefor comprising an actuating device, and a lever system for connecting the actuating device to the circuit breaker, said lever system including a toggle arranged to increase the ratio of movement of the actuating device to movement of the circuit breaker during the closing movement to a maximum at the moment the contacts of the circuit breaker first engage. 115
